UNITED STATES PATENT OFFICE.

JOHN CLULEE, OF WALLINGFORD, CONNECTICUT, ASSIGNOR TO THE BALDWIN JEWELRY CO., OF SAN FRANCISCO, CALIFORNIA, A CORPORATION.

DESIGN FOR A SPOON.

40,703.

Specification for Design.

Patented May 24, 1910.

Application filed April 13, 1910. Serial No. 555,315. Term of patent 7 years.

To all whom it may concern:

Be it known that I, JOHN CLULEE, a citizen of the United States, residing at Wallingford, in the county of New Haven and State of Connecticut, have invented a new, original, and ornamental Design for a Spoon; and I do hereby declare the accompanying drawings to be a full, clear, and exact illustration of the same, and which said drawings constitute part of this specification, and represent, in—

I claim:

The ornamental design for a spoon as shown.

JOHN CLULEE.
